PROTECTIVE SYSTEM

Harry J. Robinson, Needham, and Ray F. Garrison, Stoughton, Mass., assignors to The Mosler Safe Company, Boston, Mass., a corporation of New York

Application July 21, 1934, Serial No. 736,298

10 Claims. (Cl. 109—1)

This invention pertains to protective systems for banks, safe deposit vaults, etc. and to apparatus and appliances forming parts of such a system, and is intended primarily to afford protection against robberies during the working hours of the bank or other place in which the system may be installed.

While protective systems have been devised and are commonly in use, which afford reasonably good protection against the depredations of burglars during the night or at other times when the bank is closed, little real protection has been provided for during the working periods of the bank, and many robberies have occurred during such working periods and after the vaults have been opened.

The time controlled vault locking mechanisms which are in common use are usually set to allow the vaults to be opened at the beginning of the working day, and in some cases robberies have been timed to take place immediately following the unlocking of the vaults and when few customers might be expected to be in the bank. In such day-time robberies, the question of time is an all important factor, and if the intended robbery could be delayed even for a few minutes, such delay in many cases would be enough to foil the robbers' intentions. Ordinarily the intended robbers give no opportunity for closing the vault or other safety receptacle doors, and even if closed and locked, robbers may force the bank employees to open the doors unless the time mechanism be in operation so that immediate unlocking of the door is an impossibility. In order that protective apparatus be practically efficient, it should be of such character that employees will not hesitate to set it into action at the least suspicion of intended robbery, but the usual time locking mechanism employed in bank vaults is set to run for a long predetermined period so that if once set into operation it is a long time before the doors may be opened again. Thus even if it were possible quickly to restore the vault doors to time lock control, employees would be loathe to take this step until absolutely assured that a robbery was intended, and this assurance might come too late to prevent appropriate action.

We are aware that certain delayed action locks have heretofore been proposed, designed to prevent access to the contents of a vault or locker for a predetermined period after the main time lock has run down, and also that proposals have been made to actuate locking members for locker doors or the like from a remote point. How-

ever, such prior delayed action time mechanisms, so far as they are known to us, have necessitated substantial or expensive changes or alterations in the existing protective arrangements, and it is obvious that remote control of the locking devices for doors is useless unless the door or other closure having such locking device be closed before the locking device is actuated.

While we herein make reference to a vault door as illustrative of a door or other closure for a receptacle designed to hold and to protect persons or valuables, we do not intend thereby to limit ourselves to bank vault doors or even to door for lockers within bank vaults, but desire it to be understood that our invention is applicable not only to vault doors and vault locker doors but also to doors for lockers located at any desired point, to cash drawers, to the doors of tellers' cages, doors or gates giving access to private rooms or compartments, or in fact, as already intimated, to any movable closure of whatever kind or character. By way of specific example we shall hereinafter make reference to the door of a locker situated within a protected vault, for example such a locker as is commonly assigned to an individual teller in the bank. Such doors are usually provided with locks, either combination or key operated, and when the main vault door has been opened, after its controlling time mechanism has run down, the inner locker doors may be opened at any time by the teller. Thus the latter may be forced by a robber to open the locker door at any time during the working period.

In accordance with our present invention we provide a delayed action time lock for controlling the locker door, or as many such doors, cash drawers, gates or the like as may be desired. Preferably the delayed action mechanism is arranged within a casing and disposed within the protected space, for example, the main vault, but preferably this delayed action mechanism is outside of the locker itself and is designed to run only for a relatively short period, after being set, for example, fifteen minutes. To keep the locker door locked for such a limited period during working hours would not be particularly annoying, even though it might prove unnecessary, although a delay of this length in opening the locker would, in most instances it is believed, be sufficient to frustrate the plans of robbers.

This delayed action time lock is so designed as to prevent manipulation of the usual locking mechanism of the locker door until the expiration of the predetermined period of operation,

but this delayed action mechanism does not start its period of operation (culminating in the release of the door operating mechanism by manual operation) except at the instance of responsible persons.

Our improved system further provides that if, during the period of operation of the delayed action time mechanism, for example, a minute before the expiration of such period, an attempted robbery should occur, the delayed action mechanism may be instantly set back to the beginning of its normal period of operation by manipulation of a controller element at a remote point or at any of a plurality of such points, thus providing that the full predetermined period of delay shall run before the locker door is free for manual actuation.

While we here refer to a single locker door as being controlled by this delayed action mechanism, it is to be understood that as many such doors, drawers, gates or the like as desired may be under the control of a single delayed action mechanism, although if preferred, separate delayed action mechanisms may be provided for the several doors, drawers or the like, or for groups of such doors or drawers.

Our improved system further contemplates the provision of signal circuits designed to indicate, for example, by means of a lamp located at a central control station, such as a head teller's desk, when any locker door, drawer, gate or the like included within the system is unlocked. As a further feature of protection we contemplate the provision of an individually operable remote controlled lock for each locker door, drawer, gate or the like, such remote controlled locks being designed for actuation by an operator at the central control desk where the resetting controller for the delayed action time mechanism may also preferably be located. These remote controlled lock devices are so designed that none of the doors, drawers, gates, etc. included in the system may be unlocked except by the remotely located central operator, head teller or the like, who may be quartered in a properly protected or guarded compartment and who manipulates the remote locking mechanisms only in response to requests transmitted by telephone or by an appropriate signal from the individual teller, cashier or the like.

In accordance with our improved system, wherein human volition is essential to the actuation of the locking mechanism, there is no such danger of premature unlocking of the particular space under protection as exists when the retraction of the bolt-work is wholly a function of mechanical arrangements, and since in accordance with the intended operation of this system the user of the protected space is expected to close and lock the door immediately after each period of use, there is little danger that the door may be standing open when the time locking mechanism is to be put into action by the remote control.

Preferably, as above noted, the delayed action time mechanism is disposed within a casing which is protected by a suitable signal system of any known or desirable type arranged to sound an alarm or give some other form of signal if the case is tampered with in any way, while the wires which lead to this casing to furnish the necessary actuating current for the time mechanism are so disposed that if they are cut, the locking mechanism remains locked indefinitely until the wires are repaired and the flow of current is restored. Preferably also the delayed ac-

tion time mechanism is furnished with an indicator which shows at any time the extent to which it has run down, that is to say, the length of time which must elapse before the door locking mechanism may be released.

In the accompanying drawings we have illustrated the general arrangement of our improved protective system, together with details of a preferred form of delayed action time control mechanism, but with the understanding that these illustrations are merely by way of example of the broad principle of the invention, and that the latter may be embodied in other arrangements of apparatus all within the spirit of the invention as limited by the appended claims.

In the accompanying drawings

Fig. 1 is a fragmentary diagrammatic elevation showing part of a vault or safe having therein a locker, and a control unit embodying the present invention;

Fig. 1a is a diagrammatic plan view of a central control panel forming a part of our improved system;

Fig. 2 is a fragmentary elevation, to larger scale, illustrating the inner side of the door of the control unit;

Fig. 3 is a diagrammatic elevation showing the front compartment of the control unit, with the door open;

Fig. 4 is a fragmentary horizontal section substantially on the line 4-4 of Fig. 3;

Fig. 5 is a diagrammatic elevation, looking toward the front of the control unit, showing the rear compartment of the latter; and

Fig. 6 is a diagram illustrating the electrical wiring circuits of the control unit.

Referring to the drawings, Fig. 1 shows by way of example a portion of a vault or safe S which may be protected by means of any desired locking mechanism, for example a time lock, (not shown) which releases the bolt-work at the beginning of the working period. Within the vault S there is shown a locker or compartment M, representative of any number of individually protected compartments, said locker having walls 4 and a door 2. The latter is furnished with bolt-work comprising one or more bolts 3, 3^a, etc. which, when projected into locking position, enter sockets 4 in the wall 1 of the locker. These bolts may be advanced and retracted manually, and may be locked by any appropriate means, for example a combination or key controlled locking mechanism.

In accordance with the present invention, the bolt 3 has a notch or recess 5 adapted at times to receive a dog 6 carried by a lever 7 pivoted at 7^a at the inside of the door 2. The weight of the lever and dog is such that gravity tends to cause the dog to enter the notch 5 whenever the latter is in registry with the dog. When the dog is disposed within the notch 5, it is impossible to retract the bolts 3, 3^a, etc. by the manually actuatable handle, even though the usual locking mechanism be unlocked.

The lever 7 constitutes the armature of an electromagnet 8 mounted on the inside of the door 2. From the magnet coils, a wire 9 leads to a snap switch 12 mounted on a panel 11, preferably located at a point remote from the vault S; for example, the panel 11 may be at a central control station, head teller's desk, or the like, preferably in a protected or inaccessible room or compartment. The switch 12 is representative of any number of switches, such as the switches 12^a, 12^b, etc., each corresponding to one locker, 75

such as the locker M, or to any other protected cabinet, drawer, gate, shutter or the like, included within the system, and provided with a locking dog, such as the dog 6, or equivalent magnetically actuated device.

A wire 10 leads from the other terminal of the coils of magnet 8 to one end of the secondary 15 of a transformer T (Figs. 5 and 6) and a wire 13 leads from the other end of the secondary transformer winding back to the switch 12. Thus whenever the secondary of the transformer is energized, closure of switch 12 permits flow of current through the magnet 8, thereby retracting the dog 6 from the notch 5 in bolt 3 and allowing the bolt to be manually withdrawn after unlocking of the usual locking devices. However, closure of switch 12, when the secondary of the transformer T is not energized, has no effect on the magnet 8 and will not permit the door 2 to be unlocked. The arrangements hereinafter described determine when the secondary of the transformer may be energized.

The panel 11 on which the switches 12, 12^a, etc. are mounted is also furnished with signals 14, for example, incandescent lamps corresponding to each of the switches. Each of these lamps 14 is connected by wires 14^a, 14^b to a switch device K (Fig. 1) associated with the locking bolt 3 of the corresponding locker or other protected device. This switch, as illustrated in Fig. 1, comprises normally separated terminals 14^c, 14^d, and the bolt 3 is furnished with an actuating finger 14^e operative, when the bolt 3 is retracted, to close the switch K and to keep it closed so long as the door 2 remains unlocked. The circuit comprising the wires 14^a, 14^b receives current from any suitable source and thus, so long as the door 2 is unlocked the lamp 14 is lighted. The operator at the panel 11 may thus determine at a glance what doors, drawers, etc. within the protected system are unlocked.

Referring more particularly to Figs. 3, 5 and 6, a pair of lead wires 16 and 16^a, from any desired source of alternating current, furnish the power necessary for operating the control unit. These lead wires may terminate at a suitable plug, (not shown) if desired, for convenience in installing the control unit at the point of use. As herein illustrated, the control unit U comprises a casing 50 having walls 33, and is adapted to be installed in the vault S outside of the locker M or other protected device and preferably so that the door C of the unit is exposed to view. When installed in a vault or other protected space, it is desirable to connect the casing of the control unit into the usual alarm system so that any effort to remove the unit bodily or to tamper with it will cause an alarm to sound. However, it will be apparent from the following description that any serious injury to the unit, its removal, or the cutting of the lead wires 16 and 16^a leaves the door 2 or other locked element of the system in locked condition.

The lead 16 is preferably connected to a post 16^b on an insulated panel P' mounted within the casing of the control unit. From the post 16^b a wire 17 (Figs. 2, 3 and 5) leads to a resilient contact tongue 18 carried by an insulating block N (Fig. 2) mounted on the inside of the door C of the control unit. The tongue 18 carries two contacts 19 and 20 at its opposite sides, and these contacts are adapted alternatively to engage complementary contacts 21 and 22, respectively, carried by flexible tongues 23 and 24 also mounted on the block N. The contact tongue 18 also car-

ries a push rod 18^a whose free end is disposed in the path of the bolt B of the locking mechanism L mounted on the inside of the door C. The door C has a keyhole Z (Fig. 1) exposed at its outer side, and preferably the locking mechanism L is of a type requiring the successive use of a plurality of keys to unlock the door C.

From the tongue 23 a wire 25 (Figs. 2, 3 and 5) leads to a post 26 carried by an insulating panel P disposed within the casing of the control unit. From the post 26 a wire 27 leads to the central contact 35 of a three-pole tilting mercury switch 28. This switch comprises a tube supported by a lever 29 to which the tube is attached by clips 30. The lever 29 is pivoted at 31 on a stub shaft projecting from a fixed vertical partition 32 (Fig. 4) dividing the space within the casing 33 of the control unit into a forward compartment 33^a and a rear compartment 33^b. The lever 29 is furnished with an arm carrying an adjustable abutment member 29^a for a purpose hereinafter described. The switch tube 28 is provided with three contacts 34, 35 and 36 and contains a pool of mercury 37 adapted, according to the inclination of the switch tube, to connect contacts 35 and 36, or 35 and 34 respectively.

A wire 38 leads from switch contact 34 to a post 38^a carried by panel P, and from this post a wire 38^b (Figs. 5 and 6) leads to one end of the primary winding 39 of the transformer T, the latter being mounted within the rear compartment 33^b of the control unit. From the other end of the primary winding 39, a wire 38^c leads to a post 38^d carried by the panel P'. The lead wire 16^a is also connected to the post 38^d.

A wire 38^e branches from the wire 38^c and leads to a post 40 forming one terminal of the winding of a synchronous electric motor 65 (Fig. 4) which drives a clock mechanism 41 mounted on the rear side of the partition 32. From the post 40 a wire 42 leads to one end of the winding of an electromagnet 43, also mounted on the rear side of partition 32. The other end of the winding of this electromagnet is connected by a wire 44 to a post 45 (Fig. 3) carried by an insulating panel P² on the front side of the partition 32. From post 45 a flexible conductor 46 leads to one contact 47 (Fig. 6) of a tilting mercury switch 48. This latter switch comprises a tube secured to one arm of a lever 44^a (Figs. 3 and 6) pivoted on a stub shaft 44^b projecting forwardly from the partition 32. The lever 44^a has a short actuating arm 44^c for a purpose hereinafter described. The switch tube 48 contains a pool 48^a of mercury adapted at times electrically to connect the contact 47 with a second contact 49 (Fig. 6). A flexible conductor 50 leads from contact 49 to a post 51 carried by panel P², and from the post 51 a wire 52 (Fig. 3) leads to the switch tongue 24 (Fig. 2) at the inside of the door C.

A wire 53 (Fig. 3) also leads from post 51 to a post 54 (Fig. 5) carried by panel P', and to this post is also connected a wire 54^a leading to one terminal 55 of a push button switch W (Figs. 1a and 6) at the central control panel 11. A wire 56 leads from the other terminal 57 (Fig. 6) of push button switch W to a post 58 on panel P', and this post 58 is connected by a wire 58^a to post 16^b. If desired, a plug 56^a (Fig. 5) and cooperating socket may be interposed in the circuit comprising the wires 54^a and 56 to facilitate installation of the control unit.

A wire 59 leads from a post 60, forming the other terminal of the winding of the synchronous clock motor 65, to a post 61 on panel P, and from

this post a flexible conductor 62 leads to the terminal 36 of switch 28. From wire 42 a branch wire 42^a (Figs. 5 and 6) leads to one or more lamps 63 (Figs. 3 and 6) preferably connected in parallel and mounted in sockets supported on the front side of the partition 32. A wire 42^b leads from the lamps 63 to the post 26 on the panel P,—the flexible conductor 27 leading from this post to the central contact 35 of switch 28, as 10 above described.

The mechanism of the clock 41 comprises a suitable frame 64 (Fig. 5) secured to the rear side of the partition 32 and having bearings for the several rotating parts. The frame also forms 15 a support for the synchronous electric motor 65, the latter having a shaft 66 provided with a pinion 67 (Fig. 4) which drives the reducing train of the clockwork mechanism. One pinion 68 in this train is carried by a lever 69 which is so mounted 20 on a stub shaft 70, carried by the partition 32, as to permit the pinion to move bodily up and down to an extent sufficient to disengage it from its driving gear 71 and also from the gear 72 which is normally driven by the pinion 68. The 25 lever 69 constitutes the armature of the magnet 43 above described, and when the latter is energized, the lever 69 is raised and the pinion 68 is moved out of mesh with the gears 71 and 72, thus freeing the latter from the clock train.

30 The gear 72 is fixed to a shaft 73 (Figs. 4 and 5) turning in bearings carried by the frame 64, and at its rear end is furnished with a lever arm 74 having a contact face 75 adapted, when the lever is turned in a clockwise direction as viewed 35 in Fig. 5, ultimately to engage the abutment element 29^a and thereby to tilt the switch 28 so as to cause the mercury 37 to close a circuit between contacts 34 and 35.

The forward part of the shaft 73 also carries a 40 lever arm 76 (Figs. 3 and 4) which, at times, engages the arm 44^c of the lever 44^a, thus holding the mercury switch 48 in the position shown in Figs. 3 and 6 with the circuit broken between contacts 47 and 49. A clock spring 77, having 45 one end secured to the shaft 73, is so tensioned as at all times to tend to hold the shaft and the levers 74 and 76 positioned as shown in Fig. 4, and when the shaft 73 is turned in a clockwise direction as viewed in Fig. 5, the spring is placed 50 under further tension, thus strongly tending to turn the shaft 73 reversely whenever the shaft is free from the clock mechanism.

At its forward end, shaft 73 carries the shutter 78 which is interposed between the lamps 63 and 55 a series of apertures 79 (Figs. 2 and 4) in the door C of the control unit. The arrangement of the shutter is such that as the shaft 73 slowly turns, one after another of the apertures 79 is uncovered, thus indicating at any time the extent 60 to which the shaft has turned. For example, if the clock is to run for fifteen minutes before the mechanism is released for unlocking, the apertures 79 may be spaced to show one minute intervals of elapsed time after the clock starts.

65 The operation of our improved protective system is substantially as follows, it being assumed at the outset that the main vault S is open and that the clock mechanism of the control unit has at some time during the working period turned 70 the shaft 73 in a clockwise direction as viewed in Fig. 5 until the contact surface 75 has engaged the abutment 29^a and thus tilted the switch tube 28 until the mercury has flowed into the left-hand end of the tube and completed a circuit between the contacts 34 and 35. It will also be

noted that at the outset of the turning of the shaft 73 in a clockwise direction as above noted, the lever 76, carried by the shaft 73, leaves the arm 44^c of the lever 44^a, thus permitting gravity to tilt the switch 48 to a position such that the mercury 48^a completes the circuit between the contacts 47 and 49. It may further be assumed that the door 2 of the locker M is closed and the bolts 3 and 3^a have been projected by the usual handle.

10 In preparation for the close of the working period, authorized persons, having keys to the lock mechanism L of the control unit, will so manipulate this locking mechanism as to project the bolt B into the position shown in Fig. 15 2, thus causing the contact 20 to engage the contact 22. At this time, as above noted, the contacts 47 and 49 of switch 48 are connected and the contacts 34 and 35 of the switch 28 are connected. When the bolt B is projected so as to cause contacts 20 and 22 to engage, a circuit is completed, beginning at lead 16^a and including the wires 38^c, 38^e, 42, the windings of the magnet 43, the wire 44, the switch 48, the wire 52, the contacts 22 and 20 and the wire 17 leading back to the lead wire 16. This energizes the magnet 43, thereby lifting the lever 69 and disengaging the pinion 68 from the gears 71 and 72. As soon as the gear 72 is released the spring 77 turns the gear 72 in a counterclockwise direction, 30 as viewed in Fig. 5, until the lever arm 76 carried by shaft 73 engages arm 44^c of lever 44^a, thereby tilting the switch 48 and breaking the circuit between the contacts 47 and 49. At the same time the arm 74 of lever 73 leaves abutment 29^a, thus allowing the switch 28 to drop and assume the position shown in Fig. 5, wherein the mercury 37 connects contacts 35 and 36. This is the position of the parts during the period when the vault is closed for the night, it being noted 40 that the tilting of the switch 48 breaks the circuit through the coils of the magnet 43 so that no current is flowing during the period when the vault proper is closed. In this position, switch 28 is supported by a stop 28^a.

45 At the beginning of the working period, after the vault S is opened, the authorized persons having the keys to the lock L will manipulate this lock so as to retract the bolt B, thus permitting the tongue 18 to spring to the left as viewed in Fig. 2 until the contacts 19 and 21 are in engagement. At this time, as above noted, the contacts 47 and 49 of switch 48 are disconnected, while the contacts 35 and 36 of switch 28 are connected. As soon as the contacts 19 and 21 of the door switch are connected, circuits are formed beginning at lead 16^a and extending through the wires 38^c, 38^e to the terminal 40 of the clock mechanism and thence from the terminal 60 of the clock mechanism through the wire 59 to the post 61, thence through the wire 62 to the switch terminal 36, thence through the wire 27 to the post 26, from the latter through the wire 25 to the tongue 23, thence by way of the contacts 21 and 19 to the tongue 18, and thence by the wire 17 to the lead 16, thus starting the clock mechanism into operation. At the same time another circuit is completed, beginning at the post 40 of the clock mechanism and including the wire 42, the wire 42^a, the lamp 63, the wire 42^b leading to the post 26, and thence by way of the wire 25 to the door switch comprising the contacts 19 and 21, and thence by way of wire 17 back to the lead 16, thus lighting the lamps 63.

The clock being set into motion drives the shaft 73 slowly in a clockwise direction as viewed in Fig. 5, and, as the shaft turns, the shutter 78 uncovers the apertures 79 one after another, thereby indicating the number of minutes which has elapsed since the clock started. Immediately on starting of the shaft 73 the lever 76 leaves the arm 44^a of the lever 44^b, permitting the latter to drop so as to connect the terminals 47 and 49 of the switch 48. When the shaft has turned substantially 180°, the contact surface 75 engages abutment 29^a and thus tilts the switch 28 so as to connect the contacts 34 and 35 while breaking the contact between the contacts 35 and 36.

In thus connecting the contacts 34 and 35, a circuit is formed, beginning at 16^a and extending by way of the wire 38^c to the primary 39 of the transformer T, thence by means of the wire 38^b to the post 38^a, thence by the wire 38 to the contact 34 of the switch 28, then by way of the contact 35 and the wire 27 to the post 26, thence through the wire 25 to the door switch and through the contacts 21 and 19 back through the wire 17 to the lead 16. The transformer is thus energized and the apparatus is now in readiness for control by an operator at the central control panel 17 whenever it is desired.

For example, if with the apparatus in this condition the individual teller to whom the locker M is assigned desires to obtain access to this locker, he will signal the head teller or control operator at the control panel 11 and the latter will actuate the corresponding switch 12 so as to complete the circuit which includes the secondary 15 of the transformer. Closing this circuit energizes the magnet 8 and thus lifts the dog 6 out of the notch 5 in the bolt 3 and holds the dog lifted so long as the switch 12 continues to close the secondary transformer circuit. The individual teller may now manipulate the lock mechanism of the door 2 so as to retract the bolts 3, 3^a and open the door. Immediately the bolts 3 are retracted, the circuit through the lamp 14 is completed and the operator at the central control panel 11 is apprised of the fact that the locker M is unlocked. This lamp continues to burn so long as the bolts 3 are retracted, even though the door 2 may be closed.

In accordance with the intended operation of the system, the teller to whom the locker M is assigned will, immediately after he is through working at the locker, close the door 2 and project the bolts 3 into locking position. If he fails to do this, the central control operator will note such failure by reason of the continued burning of the lamp 14, and may signal the teller to lock the door 2. As soon as the control operator notes that the lamp 14 has gone out, he will manipulate the switch so as to break the circuit through the magnet 8, thus allowing the dog 6 to drop and thus prevent local retraction of bolt 3.

If, when the clock mechanism has turned the shaft 73 either partly or wholly through the intended angle necessary to release the locking mechanism, any emergency should arise such as to make it undesirable to have the locking mechanism released, the control operator at the panel 11 will press the switch button W, thus completing the circuit beginning at the lead 16 and extending through the wires 58^a, 56, the contacts 57 and 55 of the switch W, the wire 54^a, the wire 53, the terminals of switch 48, the wire 46, the wire 44, the coils of magnet 43, the wire 42, the wires 38^c and 38^b, back to the lead wire 16^a.

This completes the circuit through the magnet 43, raises the lever 69, disengages the pinion 68 from the gears 71 and 72 and permits spring 71 to reverse the shaft 73 and bring it back to its original position in which the circuit is broken at the switch 48 and is also broken between the terminals 34 and 35 of the switch 28.

The delayed action timing mechanism comprising the clock device 41 must thus start over again at the beginning of its fifteen-minute or other predetermined period and must complete this entire period before the locking mechanism is again in releasable condition, and as often as the button at switch W is depressed the clock mechanism is obliged to initiate a new period of operation. It is thus possible at any time in the day for the control operator at the central panel 11 to set the clock mechanism of the control unit at the starting position in which all of the locking dogs 6 of the various protected devices such as lockers, drawers, etc. are in locking position and can not be released until the completion of the delayed action timing mechanism.

While a desirable embodiment of the invention has herein been illustrated by way of example, we wish it to be understood that the invention is capable of embodiment in other specific arrangements and that all such equivalent constructions as fall within the scope of the appended claims are to be regarded as within the purview of the invention.

We claim:

1. A protective system comprising a locker having a door, a manually actuatable bolt for the door, a locking dog for the bolt, motor means for retracting the locking dog, a timing mechanism operative after a predetermined interval of time to make available energy for operating said motor means, a manually operable device operative to set said timing mechanism into operation, an outer protective enclosure for the locker, and means exterior to said protective enclosure operative to determine the application of energy for driving said motor means.

2. A protective system comprising a door, bolt-work for holding the door closed, and locking means for the bolt-work comprising independent moving parts, means carried by the door for moving one of said parts, and control means for moving the second of said parts, said control means comprising a timing mechanism, and an actuator remote from the door, said timing mechanism and actuator being so interdependent that either is ineffective to move said second part except by cooperation of the other.

3. A protective system comprising a plurality of independent closures, each provided with bolt-work for holding it closed, interdependent locking means for the bolt-work of each closure, each said locking means including a plurality of independent movable parts each of which must be moved to release the bolt-work, manually actuatable means adjacent to each of the respective locking means operative to move one of said parts, and an actuator corresponding to each of said closures, respectively, arranged at a control station remote from the closures, each of said actuators being operative at times to initiate the movement of the second of the moving parts of the corresponding locking means.

4. A protective system comprising a plurality of independent closures, each provided with bolt-work for holding it closed, locking means for the bolt-work of each closure, each said locking means including a plurality of independent mov-

able parts each of which must be moved to release the bolt-work, manually actuatable means adjacent to each of the respective locking means operative to move one of said parts, a manually operable actuator corresponding to each of said closures, respectively, arranged at a control station remote from the closures, each of said actuators being operative at times to initiate the movement of the second of the moving parts of the corresponding locking means, and a time mechanism operative to determine the period of time within which any of said actuators may initiate movement of the second of the moving parts of the respective locking mechanisms.

15. 5. A protective system comprising a plurality of independent closures, each provided with bolt-work for holding it closed, locking means for the bolt-work of each closure, each said locking means including a plurality of independent movable parts each of which must be moved to release the bolt-work, manually actuatable means adjacent to each of the respective locking means operative to move one of said parts, a manually operable actuator corresponding to each of said closures, respectively, arranged at a control station remote from the closures, each of said actuators being operative at times to initiate the movement of the second of the moving parts of the corresponding locking means, a time mechanism operative to determine the period of time within which any of said actuators may initiate movement of the second of the moving parts of the respective locking mechanisms, and means at the control station operative at will to reset the timing mechanism to its starting position.

6. In a protective system of the class described comprising a protected space, a closure arranged within the protected space, locking means for the closure, a lock controlling time mechanism also within the protected space, said time mechanism comprising a rotary shaft, a motor, a train of mechanism normally transmitting motion from the motor to the shaft whereby to turn said shaft through a predetermined angle, a part carried by the shaft operative at the end of a predetermined angle of movement of the shaft to release the lock means from time control, thereby to permit the closure to be unlocked, spring means tending to turn the shaft in opposition to the motor, disconnecting means operative to break the train of connections between the motor and the shaft, thereby to permit the spring to reverse the shaft, and means comprising a part remote from the protected space operative at will to actuate said disconnecting means.

7. In a protective system of the class described comprising a burglar-resistant vault, a closure arranged within the vault, locking means for the closure, a lock controlling time mechanism also within the vault but outside of the closure, said time mechanism comprising a rotary shaft, a resetting element constantly tending to turn the shaft in one direction, a motor for turning the shaft in the opposite direction, means carried by

the shaft operative after the shaft has turned through a predetermined angle to release the lock means from time control, thereby to permit the closure to be unlocked, and means including an actuator remote from the protected space operative to disconnect the shaft from the motor thereby to permit the resetting element to restore the shaft to starting position.

8. In a protective system of the class described having a closure provided with bolt-work for holding it closed and with lock means for the bolt-work, said lock means comprising independent movable parts, means for moving one of said parts, electromagnetic means for moving the other of said parts, and a control unit comprising a casing which encloses time mechanism, key controlled means within the casing for starting the time mechanism into action, an electric switch within the control unit casing, said switch being under control of the time mechanism and operative at the end of a predetermined period of operation of the time mechanism to supply electrical energy to a circuit including said electromagnetic means, and means including a part remote from the closure operative to close said circuit, thereby to energize said electromagnetic means when current is supplied to said circuit.

9. A protective system comprising a locker having a movable closure, a manually actuatable bolt for the closure, a locking dog for the bolt, electromagnetic motor means for releasing the dog, timing mechanism normally operative after a predetermined interval of time to close an electrical circuit constructed and arranged to supply energy to the electromagnetic motor means, manually operable means adjacent to the closure operative to set the timing mechanism into action, an outer protective enclosure for the locker, means exterior to said protective enclosure operative to initiate the supply of energy to said electromagnetic motor means, and means also outside of the protective enclosure operative at will and as many times in succession as desired to reset the timing mechanism to the starting point.

10. A protective system comprising a locker having a movable closure, a manually actuatable bolt for the closure and manually actuatable locking means for the bolt, an auxiliary locking device for the bolt, electromagnetic means for releasing said auxiliary locking device, timing mechanism normally operative after a predetermined interval of time to close an electrical circuit constructed and arranged to supply energy to said electromagnetic motor means, manually operable means adjacent to the closure operative to set the timing mechanism into operation, means providing a protected space remote from the locker, means within said protected space operative to initiate the supply of energy to said electromagnetic motor means, and means also within said protected space operative at will to reset the timing mechanism to the starting point.
